LOOM HAVING INDEPENDENT LAY AND WEFT INSERTING MECHANISMS

John S. Chaya, Springfield, Pa., assignor to American Viscose Corporation, Philadelphia, Pa., a corporation of Delaware

Application June 5, 1952, Serial No. 291,960

10 Claims. (Cl. 139—191)

The present invention relates to looms in which the operations of beating-up the weft and the insertion of weft between the separated warp threads of the shed are conducted synchronously but by separate mechanisms. The invention is concerned particularly with the type of loom that comprises a shuttle and a race-way therefor.

In the conventional loom, the beating-up of the weft is accomplished by a reciprocal movement of the lay after insertion of a course of weft yarn by the shuttle. A tire fabric loom in which the lay, the reed, and the shuttle are combined in one reciprocating assembly having a length of, e. g., 72 inches which corresponds to the standard width of tire fabric, may be operated economically at speeds up to 172 picks per minute. A textile fabric loom of comparable size is operated at a somewhat lower speed such as one in the range of 130 to 140 picks per minute. Such speeds exemplify the maximum rates at which looms of this size may be operated without excessive wearing and breakage of such parts as the picker, picking cam, picker stick, lug straps, shuttle box lining, picking nose, and picking arm.

Various attempts have been made to accomplish beating-up the weft and the transfer of the shuttle by separate mechanisms so as to restrict the function of the assembly for projecting and guiding the shuttle to that of merely transferring the shuttle transversely through the warp shed. By such an arrangement, it was believed that wear imposed upon the lay assembly by the reciprocation thereof lengthwise of the warp could be eliminated and higher weaving speeds could be attained. However, none of the systems of the prior art have been commercially accepted when applied to looms of the size used for weaving tire fabrics because of complexity of structure, maintenance difficulties, or lack of satisfactory operation.

It is an object of the present invention to provide a loom having separate mechanisms for inserting the weft into the warp and for beating-up the weft. It is another object to provide a loom for weaving fabrics of widths of 5 feet or greater having a shuttle race-way whereby weft may be inserted at rates of 200 or more picks per minute without excessive wear of the loom. It is also an object to provide a loom in which the mechanisms for beating-up the yarn and inserting the weft may be operated with substantially fewer breakdowns and less maintenance costs than when operating conventional looms. Other objects and advantages will become apparent in the following description of the invention and the drawing relating thereto in which

Fig. 1 is a partly diagrammatic illustration of a loom showing in section a unitary beating-up assembly thereof constructed in accordance with the invention;

Fig. 2 is an enlarged section view taken along line II—II of Fig. 3 illustrating the portion of the loom shown in Fig. 1 comprising the independent lay or beating-up assembly;

Fig. 3 is a fragmentary view of the apparatus illustrated in Fig. 2;

Fig. 4 is a geometric representation of cyclical move-

2

ments effected by reciprocating portions of the independent lay assembly shown in the other figures; and

Fig. 5 is a partial and partly diagrammatic plan view of the loom illustrated in Fig. 1.

In brief, a loom of the present invention comprises a shuttle, a stationary race-way for the shuttle, a reciprocable lay supported movably and independently of the race-way and comprising a comb for cyclically entering the warp shed to beat-up a weft yarn and then withdrawing therefrom during a return movement, slide members for supporting the lay in slidable relationship with a stationary axis, and a cam and crank assembly for engaging elements in fixed relationship with the slide members to effect simultaneous vertical and horizontal movement thereof, whereby the lay is moved through a circuitous or ovate path in timed relationship with the movement of the shuttle.

As shown in Fig. 1, a large plurality of warp threads 5 are drawn into a loom 6 in the direction indicated by 20 the arrow from a supply source not shown. The warp threads pass between a plurality of snubbing rolls 7 through harnesses 9 and 10 which reciprocate in a vertical direction to open separate groups of the warp threads 5a and 5b which form a shed 11.

A stationary race-way 12 for a shuttle 14 comprises a reed 15 and may be attached directly to the frame 16 of the loom. In accordance with conventional loom construction, the shuttle is received at each end for the race-way within the "boxes" 13 and projected therefrom along the raceway by picker sticks 13a as shown in Fig. 5. Due to the insertion of the weft yarn between the warp threads forming the shed, an interwoven fabric 17 is formed at 18 which passes over the guide bar 19 and under another guide bar 20. A pair of rotary temples 21 engage upper 25 marginal surfaces of the fabric as it passes over the guide bar 19 to prevent the fabric 17 from contracting in a widthwise direction. The fabric 17 is drawn through the loom at a desired linear rate by a take-up roll 23. Contact therewith is promoted by a guide roll 24 having an axis parallel to that of the take-up roll and disposed relatively thereto, such as in the manner shown, to hold the fabric in contact with sufficient area of the take-up roll to insure traction. The fabric 17 passes thereafter to a beam 27 on which the fabric is collected. The beam 27 is rotated by any suitable slip-drive system such as a motor 28 connected in driving relationship with the beam by a loose belt 29.

An important feature of the loom is a unitary assembly 31 for beating-up the weft yarn within the shed 11 into the confluence of the divided warp threads adjacent the guide bar 19. The assembly 31 comprises a comb 32, a pair of supporting slide members or bars, such as slide member 33, extending upwardly toward the opposite ends of the comb, and a pair of brackets or fixtures, such as bracket 34, for attaching the comb to the slide members. The other slide member is a mirror replica of the member 33. The assembly 31 of the loom herein described is equivalent to the lay of the conventional loom and may be designated, if desired, by that term. The reed of the reciprocating race-way of a conventional machine engages the weft in accomplishing the beating-up thereof; in the present machine this is done by the comb. In Fig. 5 the comb 32 is shown in the position wherein, during operation, it is below the warp 11 and moving toward the raceway 12.

The slide members are moved and mounted within assembly 31 by duplicate structure, such as that illustrated in detail in Figures 2 and 3 for supporting the member 33. The member 33 has two slots 35 and 36 which are elongate in a direction substantially parallel to the lengthwise direction of the member. The lower slot 35 re-

ceives a slide block 37 supported rotatably on a stud or axle 38 which is secured fixedly on a frame portion 41 of the assembly 31. Another slide block 43 extends widthwise in the slot 36 and travels lengthwise thereof in response to the revolution of a crankpin 44 about which the slide block is pivotably mounted. The crankpin is attached to a lateral surface of a gear 45. A shaft 47 supports the gear 45 and a cam 48; the gear and the cam are secured to the shaft for rotation together. A rotatable cam follower 49 which may comprise, as shown, an ordinary roller bearing mounted on an axle 51 extending from, and fixed to, a lateral surface of the member 33. The shaft 47 is supported within a bearing 52 anchored to the frame of the assembly 31. The gear 45 is driven by another gear 54 mounted on a shaft 55 which extends transversely within the loom and is journaled within the bearings supported by the opposite frame portions of the unit 31.

The shaft 55 is connected in drive relationship with any convenient rotary portion of the loom which will operate the lay assembly in synchronism with movements of the shuttle and the harnesses. As shown, a sprocket 56 is connected in drive relationship with a sprocket 57 mounted on a main cam shaft 58 of the loom by a sprocket chain 59. During operation of the loom the gear 45, when driven by the system just described, produces revolution of the crankpin 44. The latter acts upon the member 33 to reciprocate the member and the comb 32 in a direction extending lengthwise of the warp which constitutes the shed 11. As the slide block 43 has freedom of movement lengthwise of the slot 36, the crankpin does not make any contribution to the vertical movement of the member 33. The vertical movement of this member is derived entirely from the rotation of the cam 48 mounted also on the shaft 47 for rotation with the gear 45.

The angular position of the cam 48 with respect to the crankpin 44 is fixed, so as to obtain a path of movement of the comb 32 indicated in Figure 4 by the endless ovate dotted line 61. The mechanism for traversing the comb 32, just described, occurs at one side of the assembly. A similar mechanism is duplicated in mirror image at the opposite end of the lay unit 31 so as to duplicate at both ends of the lay unit with great precision the desired motion to be effected by the comb 32. The shape of the path 61 traversed by ends of the teeth of the comb as illustrated by dotted line in Fig. 4 conforms to a preferred manner of operation but is not critical. The shape may be modified by changing the shape of the cam 48 and its mate at the opposite end of the unit 31 to any desired peripheral contour, and by changing the magnitude of eccentricity of the crankpin 44 with respect to the shaft 47.

Fig. 4 illustrates diagrammatically the movements executed by various portions of the lay and lay-reciprocating assembly. At the instant of operation depicted in Fig. 4, the comb has penetrated well into the warp shed and is moving into contact with a course 60 of weft yarn. Line 62 may be considered a longitudinal axis of the member 33 which extends through the axis of rotation of the cam follower, the axis of the crankpin 44, and the axis of the stationary axle 38. Numeral 63 indicates some point on the axis of the member 33 below the slot 35. From this figure it will be seen that the slide bar 33 pivots as well as slides longitudinally relative to the axis of the axle 38 and the bar has no horizontal movement at this point. The crankpin travels in a circle but since the crankpin moves slidably along the axis 62, the slide bar is moved only in a generally horizontal direction by the crankpin. However, the combined lifting action of the cam 48 and horizontal movement of the crank cause the axis of the cam-follower (and the axis of the slide bar 33 at that point) to traverse a path of movement indicated by the ovate dotted line 67. The path 61 traversed by the tip of the comb 32 is of the same general pattern but due to the relatively greater distance of the cam from the pivot

at 38, the motion is extended in the horizontal direction when compared to the motion of the follower. The point 63 of the slide bar 33 travels a path indicated by the dotted line 68.

However, the path of the comb as herein described and illustrated conforms to that needed to obtain rapid operation of the loom without difficulties arising such as the cam-follower losing contact with the cam in effecting rapid insertion of the comb into, and withdrawal thereof from, the warp shed such as is necessary for efficient beating-up of the weft. The terms "weft," "warp," and "thread" as used herein are not intended to limit the invention to any particular type of strands since all types of strands which may be woven on a loom are contemplated in the use of the present invention.

Although the beating-up mechanism herein described has been constructed as a unit or sub-assembly to be mounted within a loom, it may be installed in existing looms as well as in newly designed looms to eliminate the need for reciprocating the race-way of the shuttle in beating-up the weft to thus enable more rapid operation of the loom. The beating-up mechanism of the present invention may also constitute an integral portion of newly designed looms having stationary race-ways for shuttles.

As shown in Fig. 1, the unit 31 comprises spaced frame portions such as member 41 connected by another frame portion extending therebetween. The frame of the unit 31 comprising these several portions is fixedly attached to the main frame 16 of the loom. As shown, the unit 31 is mounted upon inwardly extending flanges of the loom frame, such as flange 69.

While a preferred embodiment of the invention has been shown and described, it is to be understood that changes and variations may be made without departing from the spirit and scope of the invention as defined in the appended claims.

I claim:

1. A loom comprising means for guiding a plurality of threads into substantial parallelism over a flat path to form a warp sheet of threads, means for successively opening the threads to form a shed extending widthwise of the sheet, a shuttle for inserting weft, a stationary race-way for guiding the shuttle along a path through the shed, an elongate comb having spaced teeth of a thickness adapting them to readily enter the threads constituting the shed, movable means for supporting the comb transversely with respect to path traversed by the sheet and exteriorly of the shed with the teeth extending toward the region within the shed, said movable means having guide surfaces extending in a direction away from the comb, at least one of the guide surfaces being spaced further away from the comb than another, pivotal means having an axis extending in spaced substantially parallel relationship with the shuttle path and the shed for slidably and rotatably engaging one of said guide surfaces, crank means in engagement with one of said guide surfaces spaced differently with respect to the comb than the guide surface in engagement with the pivotal means, said movable member comprising a cam follower, a cam for engaging said cam follower to move the comb into and out of the shed, and means connecting the crank means and the cam for synchronous rotation.

2. A loom comprising means for guiding a plurality of threads into substantial parallelism over a flat path to form a warp sheet, means for successively opening the threads to form a shed extending widthwise of the sheet, a shuttle, a stationary race-way for guiding the shuttle along a path through the shed, an elongate comb having spaced teeth of a thickness adapting them to enter readily the yarns constituting the shed, movable means for supporting the comb transversely with respect to the path traversed by the sheet and exteriorly of the shed with the teeth extending toward the region within the shed, said movable means having guide surfaces extending in a direction away from the comb, at least one

of the guide surfaces being spaced further from the comb than another, pivotal means having an axis extending in spaced substantially parallel relationship with the shuttle path and the shed for slidably and rotatably engaging one of said guide surfaces, crank means in engagement with one of said guide surfaces spaced differently with respect to the comb than the guide surface in engagement with the pivotal means, cam following means fixed to said member, a cam connected with the crank means for rotation about a common axis, said cam engaging the cam following means to move the comb into and out of the shed in synchronous reciprocal movement of the comb lengthwise of the path traversed by the sheet effected by the crank means.

3. A loom comprising means for forming a continuous sheet of warp threads, means for successively separating the threads of the sheet to form a shed extending the entire width of the sheet, a shuttle for carrying a supply of weft thread, means connected in synchronism with the separating means for projecting the shuttle from one side of the sheet to the other through the shed after each separation of the threads, and means for beating-up the weft within the shed comprising a comb, means for supporting the comb with its lengthwise direction extending transversely with respect to the longitudinal direction of the sheet, the teeth of the comb extending toward the interior of the shed, said supporting means having cam-following means fixedly associated therewith and having guide surfaces aligned in a direction extending away from the comb and the sheet, one of said surfaces being closer to the comb than another, pivotal means having an axis spaced from the sheet and extending in a direction substantially parallel to the widthwise direction of the sheet, crank means having an axis of rotation parallel to the axis of the pivotal means and in spaced relationship therewith, one of said guide surfaces being engaged by the pivotal means in slidable and rotatable relationship and the crank means being in slidable and rotatable relationship with one of said guide surfaces that is spaced differently from the comb than the one in engagement with the pivotal means, and cam means connected with the crank means for synchronous rotation therewith for engaging the cam following means, said cam means being disposed relatively to the crank means and the pivot means to move the comb into and out of the shed.

4. A loom comprising means for forming a continuous sheet of warp threads, means for guiding the warp threads and the fabric derived therefrom along a flat path through the loom, means for successively separating the threads of the sheet to form a shed extending the entire width of the sheet, a shuttle for carrying a supply of weft thread, a stationary race-way defining the path of the shuttle through the shed, means associated with the race-way connected in synchronism with the separating means for projecting the shuttle from one side of the sheet to the other through the shed after each separation of the threads, and means for beating-up the weft within the shed comprising a comb, means for supporting the comb with its lengthwise direction extending transversely with respect to the longitudinal direction of the path, the teeth of the comb extending toward the interior of the shed, said supporting means having cam following means fixedly associated therewith and guide surfaces aligned in a direction extending away from the comb and the sheet, one of the said surfaces being closer to the comb than another, pivotal means having an axis spaced from the sheet and extending in a direction substantially parallel to the widthwise direction of the path and into slidable and rotatable engagement with one of said guide surfaces, crank means having an axis rotation parallel to the axis of the pivotal means and in spaced relationship therewith, one of the said guide surfaces that is spaced differently than the one engaged by the pivotal means being engaged by the crank means, and the cam means con-

5
6
nected with the crank means for synchronous rotation therewith for engaging the cam following means, said cam means being disposed relatively to the crank means and the pivotal means to move the comb into and out of the shed.

5. A loom comprising means for forming a continuous sheet of warp threads, means for guiding the warp and the fabric derived from the warp along a flat path through the loom, means for successively separating the threads of the sheet to form a shed extending the entire width of the sheet, a shuttle for carrying a supply of weft thread, means connected in synchronism with the separating means for projecting the shuttle from one side of the sheet to the other through the shed after each separation of the yarn, means for beating-up the weft within the shed comprising a comb, two elongate support members attached to and extending from spaced portions of the comb in a direction extending away from the path followed by the warp threads, said comb having teeth extending towards the path and being supported with the lengthwise direction thereof extending transversely with respect to the longitudinal direction of the path, each of said support members having a pair of guide surfaces, each guide surface extending in the direction lengthwise of its respective member, one surface of each pair being closer to the comb than the other, pivotal means having an axis spaced from the path and extending in a direction parallel to the widthwise direction of the path, said pivotal means engaging corresponding guide surfaces of each member, crank means having an axis of rotation parallel to the axis with the pivot means and in spaced relationship therewith, said crank means engaging the other two guide surfaces of said members in continuous contact therewith, each of said members having cam following means affixed thereto and a pair of cams having identical peripheries, each cam being engaged with the cam following means of one member, means for connecting the cams with the peripheries thereof in identical angular relationship with their axis, and means for connecting the cams with the crank means for synchronous rotation, said cam means being disposed relatively to the crank means and the pivot means to move the comb into and out of the shed.

6. A loom comprising means for forming a continuous sheet of warp threads, means for guiding the warp thread and the fabric derived therefrom along a flat path through the loom, means for successively separating the threads of the sheet to form a shed extending the entire width of the sheet, a shuttle for carrying a supply of weft thread, means connected in synchronism with the separating means for projecting the shuttle from one side of the sheet to the other through the shed after each separation of the threads, and means for beating-up the weft thread within the shed comprising a comb, means for supporting a comb with its lengthwise direction extending transversely with respect to the longitudinal direction of the path, the teeth of the comb extending toward the interior of the shed, said supporting means having cam following means fixedly associated therewith and having guide surfaces aligned in a direction extending away from the comb and the path, one of such surfaces being closer to the comb than another, pivotal means having an axis spaced from the path and extending in a direction parallel to the widthwise direction of the path, said pivotal means being in substantial engagement with said surface which is farther from the comb, crank means having an axis of rotation parallel to the axis of the pivotal means and in spaced relationship therewith, said crank means being in substantially continuous engagement with said guide surfaces that are nearer the comb, and cam means connected with the crank means for synchronous rotation therewith for engaging the cam following means, said cam means being disposed relative to the crank means and the pivotal means to move the comb into and out of the shed.

7. A loom comprising means for forming a continuous

7
sheet of warp threads, means for guiding the warp and the fabric derived therefrom along a flat path through the loom, means for successively separating the threads on the sheet to form a shed extending the entire width of the sheet, a shuttle carrying a supply of weft thread, means connected in synchronism with the separating means for projecting the shuttle from one side of the sheet to the other through the shed after each separation of the threads, and apparatus adapted to be mounted as a unit within the loom for beating-up the weft comprising a stationary frame, a comb, movable means for supporting the comb with its lengthwise direction extending transversely with respect to the longitudinal direction of the path, the teeth of the comb extending toward the interior of the shed, said supporting means having cam following means attached thereto and guide surfaces aligned in a direction extending away from the comb and the path, one of said surfaces being closer to the comb than another, pivotal means extending from the frame along an axis spaced from the path in a direction substantially parallel with the widthwise direction of the path, coaxial crank means and cam means having an axis of rotation in parallel and spaced relationship with respect to the axis of the pivotal means, the crank means and the cam means being connected for rotation together and being rotatably supported by the frame, the cam means being in substantially continuous engagement with the cam following means, the crank means being in substantially continuous engagement with one of the guide surfaces nearer the comb, and the pivotal means being in substantially continuous engagement with a guide surface farther from the comb than the one in engagement with the crank means.

8. Apparatus for beating-up a weft thread within the warp shed of a loom comprising a frame having spaced side portions, a drive shaft extending between, and being rotatably supported by the side portions, two drive assemblies separately and rotatably supported by said side portions on a common axis of rotation, each assembly comprising a shaft and a cam, a crankpin, and a gear supported on the shaft, gears mounted on the drive shaft in separate meshing relationship with the gears of said assemblies, the working surfaces of said cams being identical and connected with respect to said axis in identical angular relationship with the drive shaft, the crankpins being disposed at equal distances from said axis and in parallel directions therefrom, pivotal means extending from the side portions along a single axis, a pair of elongate movable members, each member having a pair of slots, the slots of each pair being spaced lengthwise of the respective member with the lengthwise direction of each slot extending in substantial agreement with the lengthwise direction of the member, each slot of one member being parallel in lengthwise direction and disposed approximately equidistantly from said axis of ro-

5 tation as one slot of the other member, each member having cam following means attached thereto and being supported by the adjacent assembly with the crankpin thereof extending into one slot, the pivotal means extending from the adjacent side portion of the frame into the other slot, and the cam in engagement with the cam follower, said apparatus comprising also a comb attached to, and supported between, the members.

9. Apparatus as defined in claim 8 wherein the axis 10 of pivot means is further from the comb than the axis of the drive assemblies, and the pivotal means extends into the slot of each member which is farther away from the comb.

10. A loom comprising guide means for forming a 15 plurality of continuous threads into a warp sheet and thereafter guiding the warp sheet and the fabric derived therefrom through the loom; a plurality of reciprocating harnesses for separating the threads of the sheet to form a shed extending the substantially entire width of the sheet; a shuttle for carrying a supply of weft thread; a stationary race-way for the shuttle comprising a reed extending transversely through the region in which said shed is formed; means associated with the race-way and connected in synchronism with the harnesses for projecting the shuttle from one side of the sheet to the other through the shed after each separation of the thread; and means for beating-up the weft within the shed comprising a comb, a pair of members attached to and extending transversely from the comb in a direction extending away from the shed of the warp sheet, each member having at least a pair of guide surfaces, both surfaces extending lengthwise of its respective member with one of the surfaces being disposed generally closer to the comb than the other, said members having cam following means attached thereto, stationary pivotal means extending along a common axis into engagement with the guide surface of each member that is furthest from the comb, cam means and crank means supported on a common axis parallel to the axis of the pivotal means, said cam means continuously engaging the cam following means, the crank means being in continuous engagement with the guide surface of each member that is nearer the comb, said cam and crank means being connected in timed relationship with the shuttle-projecting means and the harnesses to move the comb into and out of the shed after each insertion of a weft thread therethrough.
